UNITED STATES PATENT OFFICE.

LOUIS VICTOR THOMAS, OF LYON, FRANCE, ASSIGNOR TO LA SOCIETE ANONYME DU MOTEUR L. THOMAS, OF LYON, FRANCE.

PISTON FOR INTERNAL-COMBUSTION ENGINES.

1,410,776.

Specification of Letters Patent. Patented Mar. 28, 1922.

Application filed July 8, 1919. Serial No. 309,325.

To all whom it may concern:

Be it known that I, LOUIS VICTOR THOMAS, a citizen of the French Republic, of Lyon, France, have invented certain new and useful Improvements in Pistons for Internal-Combustion Engines, of which the following is a specification.

In explosion motors in which the piston controls the distribution, including two-stroke cycle motors with or without valve, the pistons have hitherto been comparatively large and complicated, which makes the manufacture thereof difficult and involves considerable weight, especially in the case of two-stroke cycle pistons and pistons shaped at the base to form a deflector, and the conditions are unfavorable for obtaining perfect balance and high speeds.

In order to partly obviate these drawbacks, such pistons have been made of aluminium; but this in no way facilitates the manufacture of the piston, any more than it enables the piston to be exactly balanced. On the other hand, the aluminium, being comparatively soft, especially at high temperatures, is liable to become worn at the rings, and for that reason is not always sufficiently gas-tight.

The object of this invention is to obviate these disadvantages.

According to the invention the piston is constructed in three parts.

One of these parts, of aluminium or equivalent light metal or alloy, forming the body of the piston is of perfectly cylindrical shape, open at both ends, giving access to all its parts.

Another part, also of aluminium or equivalent light metal or alloy, forms the bottom, and is screwed to the first part: this second part can also be worked throughout.

The third part is of steel and is forced onto the two other parts: it has the grooves or channels for the piston rings.

The various parts are designed in detail as required to fulfil the distributive functions of the piston in the particular type of motor in which it is used.

The invention will now be described with reference to the accompanying drawing, showing one form of construction, by way of example.

Fig. 1 is a vertical section of the piston, and

Fig. 2 a plan view.

The piston shown has two orifices *a* and *b*

arranged to register at the proper times with the supply port *c* and the exhaust port *d* respectively. It also has a deflector *e* directing the admitted gases to the top of the cylinder to prevent their mingling with the burnt gases.

The cylindrical part *f* of the piston, of aluminium, is open at both ends: it is screw-threaded internally at *g*, in order to receive the head *h*, also of aluminium. The latter, with the deflector *e* which forms part of it, can be easily worked throughout before mounting the part. The junction of the head with the body can be completed by a band of autogenous solder. After joining these two members they are turned down or reduced in diameter over a suitable part of their length to receive a steel sleeve *j* previously bored. Then the outer surface of the piston is finished and the grooves for the rings are cut in the sleeve *j*.

The sleeve *j* has the orifices *a* and *b*, and the shape of the valve renders it very easy to properly adjust these orifices and to regulate exactly, with respect to the ports *c* and *d* of the cylinder, the times of opening and closing the inlet and the exhaust.

The invention allows of first opening the port of the cylinder, discharging products of combustion before the admission of the fresh gases, and closing the exhaust port during a large part of the period of supply. The two parts are only open together for a very short time.

What I claim as my invention and desire to secure by Letters Patent of the United States is:—

In an internal combustion engine piston the combination of a cylindrical piston body of light metal externally reduced in diameter at its upper part, a piston head of light metal screwed into the upper part of said cylindrical body, a gas deflector on said piston head, integral therewith, and a steel sleeve fitted upon the reduced upper part of said body, said sleeve extending upwardly around said piston head and said deflector and having ports.

In witness whereof I have signed this specification in the presence of two witnesses.

LOUIS VICTOR THOMAS.
